UNITED STATES PATENT OFFICE.

GUY V. LEWIS, OF HOUSTON, TEXAS.

DEVICE FOR UNSCREWING AND DRAWING PIPES.

1,420,044.

Specification of Letters Patent. Patented June 20, 1922.

Application filed September 27, 1921. Serial No. 503,691.

To all whom it may concern:

Be it known that I, GUY V. LEWIS, a citizen of the United States, residing at Houston, in the county of Harris and State of Texas, have invented certain new and useful Improvements in a Device for Unscrewing and Drawing Pipes, of which the following is a specification.

This invention relates to new and useful improvements in a device for unscrewing and drawing pipe.

The object of the invention is to provide a device of the character described by means of which joints of pipe which have become stuck in a well bore may be unscrewed and separated and withdrawn from the bore.

In drilling oil and other wells, the pipe often becomes stuck in the bore and it sometimes becomes impossible to withdraw the entire string at one time, in which case it becomes necessary to "backoff" or unscrew one or more joints at a time to withdraw the entire string. The joints of pipe in most common use are right hand threaded and in "backing off" or unscrewing the joints, a string of pipe having left hand threads must be employed to the lower end of which a fishing tool is attached which engages with the upper section of the string being withdrawn to unscrew the same. This necessitates keeping on hand a string of pipe having left hand threads which adds considerable expense to drilling operations. It is the object of this invention to provide a device by means of which the joints of the string to be withdrawn may be "backed off" or unscrewed without the necessity of maintaining a string of left hand threaded pipe, the device herein described being much lighter, simpler and cheaper than means now commonly employed for a similar purpose.

With the above and other objects in view, the invention has particular relation to certain novel features of construction, operation and arrangement of parts, an example of which is given in this specification and illustrated in the accompanying drawings, wherein:

Figure 1 is a side elevation of the device.
Figure 2 is a vertical sectional view, thereof, and

Figure 3 is a transverse sectional view, taken on the line 3-3 of Figure 2.

Referring now more particularly to the drawings, wherein like numerals of refer-

figures, the numeral 1, refers to a cup shaped casing, having a cap 2, threaded thereon. The casing has a bearing 3, through its lower end, and the cap is provided with an aligned bearing 4, and rotatably mounted in these bearings are the stems 5 and 6. These stems have the discs 7 and 8, respectively, fixed thereon, interposed between which and the adjacent bearings 3 and 4 are anti-friction rollers, provided for the usual purpose. Underneath the bearing 3 is a collar 9, which is fixed upon the stem 5, and above the bearing 4 is a similar collar 10, fixed upon the stem 8. By this construction, the stems 5 and 6 are fixed against endwise movement. The inner ends of the stems 5 and 6 have the bevel gear wheels 11 and 12, respectively, fixed thereon. These gear wheels are spaced apart and are in mesh with the pinions 13, which are located between them, and which are rotatable upon suitable spindles, projecting inwardly from the wall of the casing 1.

In operation, the stem 6 is rotated from the pipe 14, which is connected to the upper end thereof, through the collar 15, the pipe 14 being rotated by means of the well known rotary or through any other suitable means, said rotary turning in the usual direction for drilling with ordinary pipe. The casing 1 is held against rotation relative to the well casing 18 by means of dogs 19 carried by the casing 1 and whose free ends are adapted to engage with the well casing 19, so that the rotation of the stem 6 will be transmitted through the bevel gear wheels 11 and 12, and the pinions 13, to the stem 5, which will thereby be rotated in the opposite direction. The lower end of the stem 5 carries a fishing tool 16, which engages with the pipe 17, to be withdrawn, and it is obvious that when the fishing tool engages with the upper joint of said pipe 17, the same will be "backed off" or unscrewed and may then be withdrawn.

The discs 7 and 8 and the collars 9 and 10, sustain the end thrust imparted by the stems 5 and 6, and thus protect the bevel gear wheels 11 and 12, and the intermediate pinions 13.

What I claim is:

1. A device of the character described, including a casing, adapted to be let down into a well, relatively rotatable members operating in bearings therein, bevel gear wheels

rotatable pinions anchored to the casing, and interposed between and in mesh with said gear wheels, and means for fixing the casing against rotation in the well.

5 2. A device for unscrewing pipe in a well, including a casing, adapted to be let down into said well, a shaft, having a bearing in said casing, a fishing tool carried by the lower end of said shaft and adapted to engage with the pipe to be unscrewed, a cap fitted onto said casing and inclosing the same, said cap being provided with a bearing, a shaft rotatable in said last mentioned bearing, means for rotating said last men-

tioned shaft, bevel gear wheels fixed upon the adjacent ends of said shafts, pinions anchored to the casing and located between and in mesh with said bevel gear wheels, and dogs carried by the casing, and adapted to engage with the walls of the well to fix the casing 20 against turning therein.

In testimony whereof I have signed my name to this specification in the presence of two subscribing witnesses.

GUY V. LEWIS.
